(57) **CLAIM**

The ornamental design for a supporting frame of child carrying device, as shown and described.

DESCRIPTION

FIG. 1 is a front, right side, top perspective view of a supporting frame of child carrying device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a front, right side, top perspective view thereof, showing a storage basket added on rods of the supporting frame;

FIG. 9 is an enlarged view of part "9" in FIG. 6; and,

FIG. 10 is an enlarged view of part "10" in FIG. 6.

The dashed broken lines in the drawing depict portions of the supporting frame of child carrying device that form no part of the claimed design.

The dashed broken lines depict environment of the storage basket in FIG. 8 that forms no part of the claimed design.

1 Claim, 10 Drawing Sheets
